UNITED STATES PATENT OFFICE.

GERTRUDE G. CONDON, OF OAKLAND, CALIFORNIA.

HAIR CURLER.

Application filed October 7, 1922. Serial No. 593,080.

To all whom it may concern:

Be it known that I, GERTRUDE G. CONDON, a citizen of the United States of America, and resident of Oakland, in the county of 5 Alameda and State of California, have invented certain new and useful Improvements in Hair Curlers, of which the following is a specification.

This invention relates to hair curlers, and 10 particularly to a curler designed primarily for use in curling what is known as "bobbed hair", and it has for an object the provision of novel means whereby the ends of hair may be clamped or held while the hair is 15 being wrapped around the curler; and the said invention furthermore has for an object the provision of means for holding the hair clamping elements in operative relation to each other, and the provision of novel 20 means for preventing unwinding or unwrapping of the hair after the curler has been applied.

It is a further object of this invention to 25 provide a curler of the character indicated which can be readily removed from the curl without unwinding the same, so that the effect of the curling action will not be impaired or unduly affected as the curler is removed.

30 It is a further object of this invention to provide a curler comprising comparatively few parts that will be durable as well as inexpensive to manufacture.

With the foregoing and other objects in 35 view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in perspective 40 of a curler embodying the invention;

Figure 2 illustrates a sectional view thereof;

Figure 3 illustrates a view in elevation of 50 the curler in operative position, partly in section; and

Figure 4 illustrates an enlarged sectional view on the line 4—4 of Fig. 3.

In these drawings, 5 denotes what might be termed the body of the curler which preferably comprises a textile covering for a core 6, the said core being of relatively rigid

and yet pliable metal in order that it will retain its shape when bent, as will presently appear.

A clamping element or plate 7 is partially imbedded in the body, but it has an exposed end terminating in an eye 8 which acts as a guard for the loop or clip 9 which is slidable on the plate 7. The plate preferably has an integral tongue or coacting clamping element 10 which is movable so that it will assume the position shown in Fig. 1 when the hair is to be inserted between the said tongue and body or plate, and said tongue is engaged by the loop or clip, in order that it may be 70 retained in operative position with relation to the coacting parts of the curler.

After the device has been adjusted to the position shown in Figure 1, the curler is turned to wind the hair around the said 75 curler, and thereafter, the ends of the body are bent to overlie the clamp and the ends overlie each other, as fully shown in Fig. 3, a condition which prevents unwinding of the hair, or the displacement of the curler 80 therefrom.

When the curler has been in place a required time, it can be readily removed from the curl by straightening the ends of the body and releasing the tongue so that it may 85 be removed axially of the loop of the curl without disturbing the hair.

The provision of the combined pliable body and clamping device insures a more satisfactory result, in that the curler can be 90 manipulated in applying it and removing it from the hair, and it can be held in place against unwinding by the simple expedient indicated.

As shown in Fig. 2, the plate 7 is partially imbedded under a layer of fabric, and the tongue is shown as being formed as a continuation of the plate by reason of the formation of the loop 11.

It might be possible, by the use of a pintle, 100 to hinge the tongue to the plate, but the construction shown is a simpler form, and by this construction, the body and tongue can be made by the stamping processes, and hence the cost of production will be less than 105 that attending the manufacture where a hinge joint is made at the junction of the plate and tongue.

I claim:

In a hair curler, a body comprising a relatively rigid pliable core, a textile covering therefor, a clamping plate comprising a strip

of metal doubled on itself and shorter than the body, one overlapping portion of the plate being partially imbedded in the textile covering of the core, the said portion which is partially imbedded terminating in an eye constituting a guard, a loop slidable on the extending end of the partially imbedded portion having its movement limited by the material forming the eye, the other overlying section of the said plate constituting a clamping tongue adapted to press hair into

engagement with the textile covering in which a portion of the clamping plate is imbedded, and having an extension adapted to receive the loop for holding portions of the clamping plate in operative relation to each other, the ends of the body projecting beyond the clamping plate being adapted to be bent over the body and engage hair wound on the body for preventing unwind- 20 ing of the hair held by the curler.

GERTRUDE G. CONDON.
